(57) **CLAIM**

The ornamental design for dividers for a drone case, as shown and described.

DESCRIPTION

FIG. 1 is a front perspective view of a divider for a drone case.

FIG. 2 is a bottom perspective view of the divider of FIG. 1.

FIG. 3 is a left side view of the divider of FIG. 1.

FIG. 4 is a front view of the divider of FIG. 1.

FIG. 5 is a right side view of the divider of FIG. 1.

FIG. 6 is a rear view of the divider of FIG. 1.

FIG. 7 is a top view of the divider of FIG. 1.

FIG. 8 is a bottom view of divider of FIG. 1

FIG. 9 is a front perspective view of an additional divider for a drone case.

FIG. 10 is a rear perspective view of the divider of FIG. 9.

FIG. 11 is a left side view of the divider of FIG. 9.

FIG. 12 is a front view of the divider of FIG. 9.

FIG. 13 is a right side view of the divider of FIG. 9.

FIG. 14 is a rear view of the divider of FIG. 9.

FIG. 15 is a top view of the divider of FIG. 9.

FIG. 16 is a bottom view of the divider of FIG. 9.

FIG. 17 is a front perspective view of an additional divider for a drone case.

FIG. 18 is another perspective view of the divider of FIG. 17.

FIG. 19 is a left side view of the divider of FIG. 17.

FIG. 20 is a front view of the divider of FIG. 17.

FIG. 21 is a right side view of the divider of FIG. 17.

FIG. 22 is a rear view of the divider of FIG. 17.

FIG. 23 is a top view of the divider of FIG. 17.

FIG. 24 is a bottom view of the divider of FIG. 17; and,

FIG. 25 is a top view of the dividers of FIGS. 1, 9, and 17 arranged in a pattern for use in a drone case.
